UNITED STATES PATENT OFFICE.

LOUIS BLUMENTHAL, OF BROOKLYN, NEW YORK, ASSIGNOR, BY MESNE ASSIGNMENTS,
TO GEORGE HAMMEL, OF PASSAIC, NEW JERSEY.

TAG-TACKING MACHINE.

1,244,695.

Specification of Letters Patent. Patented Oct. 30, 1917.

Application filed July 18, 1916. Serial No. 109,897.

To all whom it may concern:

Be it known that I, LOUIS BLUMENTHAL, a citizen of the United States, residing at Brooklyn, in the county of Kings and State 5 of New York have invented new and useful Improvements in Tag-Tacking Machines, of which the following is a specification.

This invention relates to a machine in which the staples are automatically fed forward, and by the operation of a plunger a 10 staple is forced to pierce a tag, thereby tacking it onto a barrel or other receptacle.

One of the objects of the present invention is to provide novel means for feeding 15 the staples forward, so that one at a time will be in a line with the plunger to facilitate driving of the staples. The invention permits the use of a large magazine for the staples with a comparatively small space to 20 mount the actuating devices for moving the staples forward.

The invention comprehends means carried by the casing for housing the retrograde devices associated with the plunger, and an 25 opening in the front of the casing to afford means for adjusting the devices. The casing is practically made in two sections so that when any of the parts become disarranged the cover which forms one section can be 30 conveniently removed to expose all the mechanism.

The novel features of the invention are more fully described in the following specification and claim and illustrated in the 35 accompanying drawings in which:

Figure 1 represents a side elevation of a machine embodying this invention showing the cover removed.

Fig. 2 is a front elevation of the same.

40 Fig. 3 is a vertical transverse section taken along the line $y-y$ of Fig. 1.

Fig. 4 is an inverted plan view of the forward portion of the machine.

45 Fig. 5 is a detailed section taken along the line $z-z$ of Fig. 1.

In this drawing the letter a designates a casing which is provided with a handle b extending from the rear upper portion of the casing. A plate c adapted to cover the 50 mechanism is fastened by means of screws d to the casing. At the lower part of the casing is located a ledge e for supporting a guide bar f fastened to the ledge by screws g coacting with the casing. The bar extends from the forward to the rear part of 55

the casing and it serves as a magazine for mounting a number of staples h straddling the bar and adapted to be fed forward one by one as hereinafter described. A slide i coacts with the bar to force forwardly the staples, one of which is moved into a slot j extending to the base of the casing. The slide is provided with a lug k projecting upwardly from the rear of the slide. A coiled spring m has one end secured to the lug and the other end fastened to the stud n fixed to the casing. A chain pull o can be utilized to force the slide backward when it is desired to place the staples on the bar or otherwise.

The coiled spring is guided about a pair of idler rollers p mounted on studs q projecting from the inner portion of the casing. This method of mounting the spring in the casing allows the employment of a large 70 magazine and a small space for a long coiled spring.

The means for forcing the staples into the work includes a plunger r having a knob at its upper end and a blade s secured at s' at 80 its lower end. A spring t is mounted on the lower portion of the plunger and a collar u limits the retrograde movement of the plunger. In this device the blade co-operates with the said slot j and when the 85 plunger is pushed downward the blade will drive the pointed ends of the staple registering with the blade into the work. The invention is preferably adapted for forcing the staple to pierce a tag and be driven into 90 a box cover to firmly hold the tag. The forward rim portions of the casing and cover opposite the screw s' each have a semicircular opening to form a cylindrical opening v for the insertion of a screw driver to adjust 95 the fastening of the blade. In the lower portion of the forward end of the casing and cover is located an elongated opening w partly formed in the rim of the cover and casing to give access to the slot j when any 100 of the staples get stuck or clogged or do not feed properly. Flanges x projecting from the cover and the casing prevent upward movement of the staples and sliding device. It will be seen that all the devices for moving the staples forward and the plunger with its spring for driving the staples are 105 all assembled in the casing. The cover merely prevents any lateral displacement of the devices, and excludes dirt from the cas- 110

ing and the actuating devices; all of which including the spring for retracting the plunger are in the casing.

I claim:—

- 5 A stapling machine comprising a casing having a rim, a cover provided with a corresponding rim fitted on to the casing, a staple guide bar secured in the lower portion of the casing, a slide coating with the bar
- 10 for pushing the staples forward, a coiled spring connected to the slide and the casing, a plurality of idler rollers disposed on a line

inclined at an acute angle to the guide bar and mounted above the slide in the casing to guide the spring, and a plunger arranged in 15 the casing for driving the staples.

In testimony whereof I have hereunto set my hand in the presence of two subscribing witnesses.

LOUIS BLUMENTHAL.
